UNITED STATES PATENT OFFICE.

MARION W. PAXSON, OF VIRGINIA CITY, NEVADA.

LAMP-FILLER.

SPECIFICATION forming part of Letters Patent No. 394,720, dated December 18, 1888.

Application filed July 16, 1888. Serial No. 280,135. (No model.)

To all whom it may concern:

Be it known that I, MARION W. PAXSON, of Virginia City, in the county of Storey and State of Nevada, have invented a new and useful Improvement in Lamp-Fillers, of which the following is a specification.

My invention is an improvement in what may be termed "lamp-filters," or devices for drawing oil from a can by siphon action; and the invention consists in certain novel constructions and combinations of parts, as will be hereinafter described and claimed.

In the drawings, Figure 1 is a perspective view of the invention as in use, parts being broken away and others shown in section. Fig. 2 is a detail view of the device the tube being partly broken away and the valve cylinder or chamber being shown in section. Fig. 3 is a detail view of the valve-tube, and Figs. 4 and 5 illustrate the vent formed by grooving the threads of the fall-pipe and the valve-cylinder.

The siphon-tube A has the end of its leg A' suitably formed at *a* to cut the hole in the can for the insertion of the leg A' therein, as shown in Fig. 1, while the end of the leg or fall pipe A² is threaded at *a'*, and is provided with a groove, *a*², cut the depth of and transversely the threads *a'*, such groove forming one half or section of the vent leading into the valve-chamber B. This chamber B supports the valve, and has its upper end provided with an opening, *b*, fitted to receive the end *a'* of pipe A², such opening being threaded internally to turn on the end of pipe A', and a groove, *b*², being formed transversely of the threads *b'*. It will be seen that the grooves *a*² *b*² do not exceed in depth the threads which they intersect, so that when the grooves are out of register the threads of the cylinder and of the pipe A' will close the groove of the other part; but by bringing the grooves into register they together constitute a vent for admitting air into the chamber B for the purpose of causing the oil in said chamber, when the valve is closed, to immediately discharge.

The chamber B supports the valve C, so that the chamber is turned on threads *a'*. It and the valve move up or down with relation to pipe A², so that the valve may be moved

to and from the open end of pipe A², which forms the valve-seat, and thus adjusted to stop or permit the oil to flow into the chamber, whence it passes through ports D, and thence out of nozzle E. The valve-chamber and the end of pipe A² bear such relation that when the chamber B is adjusted to open the valve the grooves *a*² *b*² will be out of register, and will be adjusted into register when the valve is closed. Thus when the valve is closed the vent will be opened to admit air and permit the oil below the valve to immediately discharge.

By preference the valve-support is a tube 65 threaded into the lower end of chamber B, and having the notches or cut-out portions forming ports D, and having its lower end providing the nozzle. This construction is preferred, because it not only enables the convenient insertion and removal of the valve, but also enables the adjustment of said valve within the chamber, so as to secure the desired register of grooves *a*² *b*² when the valve is closed.

A brace, F, is provided to support the leg-pipe A² out from the can. In operation the tube has its pipe or leg A' applied to the can, the valve being closed. It will be understood that the tube should be filled with oil prior to its insertion in the can, or afterward, by suction or otherwise, if desired, when, by turning the chamber down pipe A², the valve may be opened and oil flow out; and the flow may be shut off by reversing the motion of chamber B, thus closing the valve and bringing the grooves *a*² *b*² into register, admitting air above the oil below the valve, and permitting same to immediately discharge, thus avoiding the necessity of supporting drip-cups below the nozzle.

In operation the filler may be attached to the can and the valve opened, when, by pressing on the sides of the can, the oil may be started and caused to flow.

Having thus described my invention, what I claim as new is—

1. The combination of the tube having threaded end *a* and groove *a*², the valve-chamber having threads *b'* and groove *b*², and the valve adjustably supported in the chamber, whereby the valve and its chamber can

be relatively adjusted to effect an accurate coincidence or register of grooves a^2 b^2 when the valve is seated, substantially as set forth.

2. The combination of the tube provided with threads a' and having a groove, a^2 , transversely of said threads, the chamber B, provided at its upper end with internal threads, b' , fitted to threads a' , and having a groove, b^2 , transversely of said threads b' , and the valve supported in said chamber, the said grooves a^2 b^2 being movable by the turning of cham-

ber B into coincidence or register, whereby when the valve is seated to close the tube a vent is produced by the coincidence of said grooves to enable the immediate discharge from the chamber of the liquid therein on the closure of the valve, all substantially as and for the purposes specified.
